UNITED STATES PATENT OFFICE.

WILLIAM M. HOERLE, OF ALLEGHENY, PENNSYLVANIA, ASSIGNOR TO THE
PITTSBURG BRASS COMPANY, OF SAME PLACE.

WICK-RAISING DEVICE FOR CENTRAL-DRAFT LAMPS.

SPECIFICATION forming part of Letters Patent No. 451,483, dated May 5, 1891.

Application filed November 28, 1890. Serial No. 372,840. (No model.)

To all whom it may concern:

Be it known that I, WILLIAM M. HOERLE, a resident of Allegheny, in the county of Allegheny and State of Pennsylvania, have 5 invented a new and useful Improvement in Wick-Raising Devices for Central-Draft Lamps; and I do hereby declare the following to be a full, clear, and exact description thereof.

10 My invention relates to wick-raising devices for central-draft lamps, its object being to provide a device whereby the wick may be raised or lowered on the central-draft tube by a gradual and steady movement, the movement 15 imparted to the wick being spiral in nature and insuring a more even adjustment of the wick with relation to the top of the wick-tube, where the wick is ignited.

To these ends my invention comprises, generally stated, a series of inclined pinions engaging with the wick, said pinions engaging with a gear-wheel adapted to be operated from without the lamp, the inclined pinions upon 25 rotating acting on the principle of the screw to impart an upward spiral movement to the wick traveling on the central-draft tube, all of which will be more fully hereinafter set forth and claimed.

To enable others skilled in the art to make 30 and use my invention, I will describe the same more fully, referring to the accompanying drawings, in which—

Figure 1 is a vertical section of a central-draft lamp embodying my invention. Fig. 2 is a plan view of my improved device, and Fig. 3 is a modified form of gearing for operating the inclined pinions.

Like letters indicate like parts.

The central-draft lamp *a* is of the ordinary 40 form, provided with the central-draft tube *b*, encircled by the wick *d*, the wick-tube, and the other parts essential to the construction of such a lamp. Near the top of the fount, within said fount, is secured the supporting-ring *e*, said 45 supporting-ring being held in place by brackets *e'*, soldered or otherwise secured to the interior faces of the fount, or held in any other convenient manner. A gear-wheel *f* is supported in any suitable manner by the supporting-ring *e*, the manner shown being well suited for the purpose, in which the said gear-

wheel is supported by the flange *e*, formed on said supporting-ring *e*. This construction provides for the rotation of the gear-wheel *f* within the flange *e*. In order to impart this 55 rotation to the gear-wheel *f*, a pinion *g*, journaled on a shaft *h*, passing through an opening in the top of the fount, engages with the outer teeth *f'* of the said gear-wheel, and upon the turning of the knob *h'* a rotary 60 movement is imparted to said gear-wheel *f*. The supporting-ring *e* is provided with the extension or journal plates *i*, extending in the direction of the wick *d*, said journal-plates *i* being arranged at an angle to the wick *d* and 65 also slightly canted to one side. Mounted on journals *j*, secured to the plates *i*, are the pinions *k*. The journal-plates *i* are arranged to approach within such a distance of the wick *d* that when the pinions *k* have been journaled thereon said pinions will engage by 70 their teeth *k'* with the body of the wick with sufficient tenacity to raise the wick upon the rotation of the pinions, as will more fully appear. The pinions *k* are adjusted at the same 75 angle to the wick as the journal-plates *i*, so that when said pinions are rotated they act, on the principle of the screw, to force the wick up spirally around the central-draft tube. The pinions *k* further mesh with the interior 80 teeth *f''* of the gear-wheel *f*. The number of pinions to be employed is to be regulated by the size of the wick.

In Fig. 3 I have illustrated another manner of operating the inclined pinions *k* by which 85 the interior teeth *f''* may be dispensed with. In this case the gear-wheel *f* is formed with the depending teeth *f'*, which engage with the pinions *k*, as shown, the said pinions being journaled in suitable bearings. The gear-wheel *f* is operated, as before, through the pinion *g*, engaging with the teeth *f'* of said gear-wheel, the principle involved being the same as that embodied in the above-described construction.

In the operation of my improved wick-raiser when it is desired to raise the wick *d* the knob *h'* is turned in the proper direction, when the gear-wheel *f*, through the pinion *g*, will be rotated. This rotation of the gear-wheel *f* will 100 in turn impart a like movement to the inclined pinions *k*, meshing with the interior

teeth f^2 of said gear-wheel. The pinions k being arranged at an angle to the wick and slightly canted to one side, with their teeth k' engaging with the wick, the rotation of said 5 pinions, acting on the principle of the screw, will impart an upward spiral movement to the wick d around the central-draft tube b . If it is desired to remove the wick entirely, it is only necessary to turn the knob h' until the 10 teeth of the pinions k have carried the wick beyond the reach of said pinions, when the wick may be readily withdrawn. A new wick may then be adjusted by hand until the lower portion of said wick is engaged by the teeth 15 of the pinions, when upon the rotation of the knob h' in the opposite direction the said pinions, acting under the same principle, will impart a downward spiral movement to the wick around the central-draft tube until the 20 desired distance is reached.

If the modified form shown in Fig. 3 be employed, the pinion g , meshed with the teeth f' of the gear-wheel f , said teeth meshing in turn with the pinions k , this operation 25 imparts the upward spiral movement to the wick in a manner similar to that shown and described above.

What I claim as my invention, and desire to secure by Letters Patent, is—

30 1. A wick-raising device having two or more pinions mounted on axes on spiral lines with relation to the central-draft tube engaging with the wick, an interiorly-toothed wheel engaging said pinion, and mechanism for rotating said gear-wheel, substantially as and for the purposes set forth.

2. A wick-raising device having two or more pinions mounted on spiral lines with relation to the central-draft tube engaging with the wick, an interiorly-toothed wheel engaging said pinions, and a pinion operated from without the fount engaging with the said wheel to rotate said wheel, substantially as and for the purposes set forth. 40

3. A wick-raising device having two or more inclined pinions engaging with the wick, and a gear-wheel having teeth on its inner face engaging with said pinions, the outer teeth of said gear-wheel engaging with a pinion operated from without the fount, substantially as and for the purposes set forth. 45

4. The combination, with the supporting-ring e , of two or more inclined pinions journaled therein engaging with an interiorly-toothed gear-wheel supported by said supporting-ring, and a pinion operated from without the fount engaging with said gear-wheel, substantially as and for the purposes set forth. 50

5. The combination, with the supporting-ring e , of the inclined brackets j , the pinions k , journaled therein, the gear-wheel f , supported by the flange e^2 , the interior teeth f^2 , engaging with the pinions k , and the pinion g , meshing with the teeth of said gear-wheel and operated by the knob h' , substantially as and 60 for the purposes set forth. 65

I testimony whereof I, the said WILLIAM M. HOERLE, have hereunto set my hand.

WILLIAM M. HOERLE.
